UNITED STATES PATENT OFFICE

154,219

DESIGN FOR A BAGGING MACHINE

Paul L. Snyder and Cecil Miller, Pomona, Calif.

Application January 19, 1948, Serial No. 143,884

Term of patent 14 years

(Cl. D55—1)

To all whom it may concern:

Be it known that we, Paul L. Snyder and Cecil Miller, citizens of the United States, residing at Pomona, in the county of Los Angeles and State of California, have invented a new, original, and ornamental Design for a Bagging Machine, of which the following is a specification, reference being had to the accompanying drawings, forming part thereof.

Figure 1 is a top plan view of a bagging machine, showing our new design;

Figure 2 is a front elevational view of the article shown in Figure 1;

Figure 3 is an elevational view taken from the right of Figure 2;

Figure 4 is an elevational view taken from the left of Figure 2.

The dominant feature of our design resides in the portions shown in full line.

We claim:

The ornamental design for a bagging machine, substantially as shown and described.

PAUL L. SNYDER.
CECIL MILLER.
